MULTILEAD MECHANICAL PENCIL

Application filed November 7, 1929. Serial No. 405,318.

This invention relates to multi-lead mechanical pencils and more particularly to a mechanical or propelling pencil having a plurality of different colored leads which can be brought separately and selectively into writing position.

One object of the invention is to provide a pencil of this character embodying novel and improved features of construction for mounting the leads in a casing and selectively presenting the leads into writing position at one end of the casing.

Another object is to provide such a pencil having novel and improved means for selecting the leads and projecting them into writing position by respective rotative and longitudinal movements in succession, whereby the operation of the pencil is simple and certain.

Other objects are to provide a pencil of the character described including a casing or holder having a single opening in one end, and a plurality of separate and independent means for mounting the respective leads within the casing, and means for selectively projecting said mounting means through said opening into writing position; to provide such a pencil having the casing formed of two relatively rotatable and reciprocable sections in one of which said mounting means is arranged, and selecting and projecting mechanism common to all of said mounting means secured in the other section for actuating them one at a time through said opening in the casing, said mechanism being brought into actuating relation to said mounting means by relative rotation of said casing sections, and actuating the mounting means by relative reciprocation of said casing sections; to provide means cooperating with said selecting and projecting mechanism for locking all except the projected one of said mounting means against movement in the casing; to

provide means for locking the projected mounting means in writing position by simple rotation of the casing sections; to provide such a mechanical pencil which shall be simple, inexpensive and reliable in construction; and to obtain other advantages

and results as will be brought out by the following description.

Referring to the accompanying drawings in which corresponding and like parts are designated throughout the several views by the same reference characters,

Figure 1 is a side elevation of a mechanical pencil embodying my invention, portions being broken away and shown in section.

Figure 2 is a similar view showing a lead carrier retracted into the casing preparatory to projecting another lead carrier.

Figure 3 is an enlarged longitudinal vertical sectional view through the pencil with the parts shown as in Figure 1.

Figure 4 is a similar view with the parts as shown in Figure 2, portions being broken away.

Figure 5 is a fragmentary longitudinal sectional view taken on the line 5—5 of Figure 4.

Figures 6 and 7 are transverse sectional views taken on the respective lines 6—6 and 7—7 of Figure 4.

Figure 8 is a transverse sectional view taken on the line 8—8 of Figure 3.

Figure 9 is a detached perspective view of the locking rod for holding the lead-carriers against projection out of the casing.

Figure 10 is an enlarged longitudinal sectional view through the lead advancing means of one of the lead-carriers, and

Figure 11 is a transverse sectional view on the line 11—11 of Figure 10.

Specifically describing the illustrated embodiment of the invention the pencil comprises a casing A which includes two tubular sections 1 and 2 which have a sliding telescoping and a relative rotative relation. At one end of one of the sections, in the present instance the section 1 is provided an opening 3 inwardly from which the walls of the section diverge or flare as at 4. In the other end of said section 1 is secured mounting means B for the leads. This mounting means is shown as comprising a plurality of lead-carriers 5 at one end of each of which is a lead holding and advancing means 6. The other end of each

lead-carrier has secured thereto a flexible rod 7 at the extremity of which is a block 8 slidable in a channel guide 9 having in-turned flanges 10 at its mouth. The channel 5 guides 9 are mounted upon a bar 11 substantially square in cross section, and the guides are secured together at their ends by rings 12 and 13, the latter of which is slotted at 14 in alinement with the mouths 10 of the respective guides 9 while the ring 12 is soldered or otherwise fixedly secured in the end of the section 1 of the casing opposite the opening 3.

In the other section 2 of the casing is 15 mounted selecting and projecting means C for the lead-carriers 5. This means is shown as comprising a sleeve 15 soldered or otherwise fixedly secured at 16 in the casing section and having a telescoping movement 20 over the guides 9. The sleeve 15 has a pin 17 projecting inwardly therefrom to enter a transverse groove 18 in each of the blocks 8 of the lead-carriers, said pin being slidable through the mouths of each of 25 the guides 9 so as to project one of the lead-carriers 5 through the opening 3 upon relative sliding movement of the casing sections 1 and 2, as shown in Figure 3 of the drawings. When the lead-carriers 5 30 are retracted into the casing, the grooves 18 of the blocks 8 are in the same transverse plane of the casing sections at right angles to the axis of the sections, as clearly shown in Figures 5 and 6 of the drawings. It 35 will therefore be obvious that by simple rotation of the casing section 2 relative to the casing section 1, the pin 17 can be located in any of the grooves 18 so as to connect with the corresponding lead-carrier for actuation of the latter through the opening 3.

It is desirable to have means for holding all except the projected one of the lead-carriers in retracted position during the actuation of one of the lead-carriers into 45 projected position through the opening 3. For this purpose I may utilize a split locking ring 19 which is rotatable in the grooves 18 and the split 20 which is of sufficient width to receive the pin 17. On the side 50 of the locking ring 19 facing the lead-carriers are a plurality of depressions or recesses 21, one for each lead-carrier, with which cooperate a locking rod 22 slidably mounted in the rings 12 and 13 and normally influenced against the locking ring 19 by a compression spring 23 interposed between a shoulder 24 on the rod and a cross-pin 25 secured in the ring 12. The recesses 21 are so arranged that when the split of the 55 locking ring is arranged in alinement with any of the guides 9, one of the recesses 21 is in alinement with the locking rod 22. The locking ring obviously will hold all but one of the blocks 8 against longitudinal movement, and the locking rod 22 will hold the 60 65

locking ring with its split in alinement with one of the guides 9 during actuation of the lead-carrier mounted in said guide. When the lead-carriers are in retracted position the pin 17 is located in the split of the locking 70 ring as shown in Figures 4 and 6, so that rotation of the casing section 2 also rotates the locking ring. The locking ring is held in position between the end of the ring 13 and a cap plate 26 secured to the end of the 75 rod 11. The cap plate 26 has the side thereof adjacent the locking ring recessed at 27 to provide a clearance for the ends of the blocks 8, as shown in Figure 5; and the cap plate serves as a stop to limit relative 80 longitudinal movement of the casing sections during retraction of the lead-carriers.

With this construction it will be understood that, assuming all of the lead-carriers 5 to be retracted into the casing as 85 shown in Figure 4, to project one of the lead-carriers through the opening 3, the sections 1 and 2 are relatively rotated until the pin 17 enters the groove 18 in one of the blocks 8. To indicate when the pin is 90 so located, one casing section may be provided on its outer surface with indicators 28 each of which corresponds in location to one of the lead-carrying members 5. The other section has an indicator 29 corresponding in position to the pin 17, or in other words in the same axial plane of the casing as said pin. Obviously when these two indicators are in alinement, the pin 17 must be located in the groove of one of the blocks 95 100 105 110 115 120 125 130 135 140 145 150 155 160 165 170 175 180 185 190 195 in, mounted therein a rotatable tube 32 which is longitudinally slotted and in which is longitudinally movable an advancing rod 33 having one end in the form of a fin 34 projecting through the slots and threaded at 35 corresponding to the threads of the tube 31. To the end of the tube 32 is secured a nib 350 in which the lead 36 is frictionally held. Obviously by rotation of the nib 350 in the proper direction, which rotates the tube 32 relative to the tube 31, the advancing rod 33 will be moved longitudinally to force the lead 36 outwardly of the nib 350 into writing position.

It is also desirable to have means for carrying a supply of leads and for this purpose the end of the casing section 2, beyond the lead-carrier projecting mechanism C may be formed into a chamber 37 closed by a plug 38 in which may be mounted an eraser 39. The eraser 39 may be protected from soil by a cap 40 frictionally fitted over the outer end of the plug 38. This cap also lends a finish to the casing.

While I have shown and described the now preferred embodiment of my invention it should be understood that this is primarily for the purpose of illustrating the principles of the invention and that many modifications and changes may be made in the details of construction without departing from the spirit or scope of the invention.

Having thus described my invention, what I claim is:

1. A multi-lead mechanical pencil comprising a casing including two relatively slidable and rotatable sections one having an opening at one end, a plurality of lead-carriers mounted in said section of the casing to move one at a time through said opening, and means in the other casing section to selectively engage said lead-carriers upon relative rotation of said casing sections and to project them outwardly through said opening and retract them into said casing upon relative sliding movement of the casing sections in opposite directions respectively, and means for locking all said lead-carriers except the one to be projected against longitudinal movement.

2. A multi-lead mechanical pencil comprising a casing including two relatively slidable and rotatable sections one having an opening at one end, a plurality of lead-carriers mounted in said section of the casing to move one at a time through said opening, and means in the other casing section to selectively engage said lead-carriers upon relative rotation of said casing sections and to project them outwardly through said opening and retract them into said casing upon relative sliding movement of the casing sections in opposite directions respectively, and means actuated by the second-mentioned section as the last-mentioned

means connects with one of said lead-carriers for locking all said lead-carriers except the one to be projected against longitudinal movement.

3. A multi-lead mechanical pencil comprising a casing including two relatively slidable and rotatable sections one having an opening at one end, a plurality of lead-carriers, a guide for mounting each lead-carrier in said casing section for individual sliding movement through said opening, means in the other casing section to selectively connect with said lead-carriers upon relative rotation of said casing sections and to project said carriers outwardly through said opening and retract them into said casing upon relative sliding movement of said casing sections in opposite directions respectively, and means on each guide cooperating with the last-mentioned means upon relative rotation of said casing sections in opposite directions when a lead-carrier is projected to lock said lead-carrier against retraction into the casing and release the lead-carrier respectively.

4. A multi-lead mechanical pencil comprising a casing including two relatively slidable and rotatable sections one having an opening at one end, a plurality of lead-carriers, a guide for mounting each lead-carrier in said casing section for individual sliding movement through said opening, each lead-carrier having a transverse groove, and all of said grooves being in a common transverse plane of the casing when said lead-carriers are retracted from said opening, and a pin on the other casing section to slide through all of said grooves when the lead-carriers are retracted so as to selectively enter said grooves of said lead-carriers upon relative rotation of said casing sections and slide the lead-carrier in opposite directions in said guide outward through said opening and inwardly into said casing respectively upon relative sliding movement of said casing sections in opposite directions, said pin being slidable in said guides to prevent rotation of said casing sections while a lead-carrier is being actuated.

5. A multi-lead mechanical pencil comprising a casing including two slidably telescoping and relatively rotatable sections one having an opening at one end and flared walls inwardly from said opening, a plurality of lead-carriers each having lead-holding means at one end to project through said opening and a flexible rod at the other end having a guide block secured thereto, a guide in said casing section slidably receiving said block of each lead-carrier, each block having a transverse groove and all of said grooves being located in the same transverse plane of said casing when the lead-carriers are retracted from said opening, and a pin on the other casing section to slide

through all of said grooves when said lead-carriers are retracted from said opening so as to selectively enter said grooves upon relative rotation of said casing sections and 5 actuate said lead-carriers in said guides to project and retract said lead-holding means through said opening upon relative sliding movement of said casing sections in opposite directions respectively, said pin being 10 slidable in said guide to hold said casing sections against rotation while a lead-carrier is being actuated.

6. A multi-lead mechanical pencil comprising a casing including two slidably telescoping and relatively rotatable sections 15 one having an opening at one end and flared walls inwardly from said opening, a plurality of lead-carriers each having lead-holding means at one end to project through said opening and a flexible rod at the other end having a guide block secured thereto, a guide in said casing section slidably receiving said block of each lead-carrier, each block having a transverse groove and all of said grooves being located in the same transverse plane of said casing when the lead-carriers are retracted from said opening, and a pin on the other casing section to selectively enter said grooves upon 20 relative rotation of said casing sections and actuate said lead-carriers in said guides to project and retract said lead-holding means through said opening upon relative sliding movement of said casing sections in opposite 25 directions respectively, and means actuated by said pin upon rotation thereof for engaging the grooves of all said blocks except the one occupied by said pin to lock all said lead-carriers except that engaged by said pin against movement in said guides.

7. A multi-lead mechanical pencil comprising a casing including two slidably telescoping and relatively rotatable sections one having an opening at one end and flared 30 walls inwardly from said opening, a plurality of lead-carriers each having lead-holding means at one end to project through said opening and a flexible rod at the other end having a guide block secured thereto, a guide in said casing section slidably receiving said block of each lead-carrier, each block having a transverse groove and all of said grooves being located in the same transverse plane of said casing when the lead-carriers are retracted from said opening, and a pin on the other casing section to selectively enter said grooves upon 35 relative rotation of said casing sections and actuate said lead-carriers in said guides to project and retract said lead-holding means through said opening upon relative sliding movement of said casing sections in opposite directions respectively, and means actuated by said pin upon rotation thereof for engaging the grooves of all said blocks except the one occupied by said pin to lock all said lead-carriers except that engaged by said pin against movement in said guides.

8. A multi-lead mechanical pencil comprising a casing including two slidably telescoping and relatively rotatable sections one having an opening at one end and flared walls inwardly from said opening, a plurality of lead-carriers each having lead-holding 40 means at one end to project through said opening and a flexible rod at the other end having a guide block secured thereto, a guide in said casing section slidably receiving said block of each lead-carrier, each block having a transverse groove and all of said grooves being located in the same transverse plane of said casing when the lead-carriers are retracted from said opening, and a pin on the other casing section to selectively enter said grooves upon relative rotation of said casing sections and actuate said lead-carriers in said guides to project and retract said lead-holding means through said opening upon relative sliding movement of said casing sections in opposite directions respectively, and means actuated by said pin upon rotation thereof for engaging the grooves of all said blocks except the one occupied by said pin to lock all said lead-carriers except that engaged by said pin against movement in said guides, and means for releasably holding said locking means in such locking position during actuation of said lead-carrier by said pin.

9. The pencil set forth in claim 4 with the addition of a locking ring having a transverse slot to receive said pin and being rotatable by said pin to engage said transverse grooves of all said lead-carriers except the one occupied by said pin to lock all said lead-carriers except that engaged by said pin against movement in said guides.

10. The pencil set forth in claim 4 with the addition of means on each guide cooperating with said pin upon relative rotation of said casing sections in opposite directions when a lead-carrier is projected to lock said lead-carrier against retraction into the casing and release the lead-carrier respectively.

transverse grooves of all said blocks except the one occupied by said pin to lock all said lead-carriers except that engaged by said pin against movement in said guides.

8. A multi-lead mechanical pencil comprising a casing including two slidably telescoping and relatively rotatable sections one having an opening at one end and flared walls inwardly from said opening, a plurality of lead-carriers each having lead-holding 70 means at one end to project through said opening and a flexible rod at the other end having a guide block secured thereto, a guide in said casing section slidably receiving said block of each lead-carrier, each block having a transverse groove and all of said grooves being located in the same transverse plane of said casing when the lead-carriers are retracted from said opening, and a pin on the other casing section to selectively enter said 75 grooves upon relative rotation of said casing sections and actuate said lead-carriers in said guides to project and retract said lead-holding means through said opening upon relative sliding movement of said casing sections in opposite directions respectively, and means actuated by said pin upon rotation thereof for engaging the grooves of all said blocks except the one occupied by said pin to lock all said lead-carriers except that engaged by said pin against movement in said guides, and means for releasably holding said locking means in such locking position during actuation of said lead-carrier by said pin.

9. The pencil set forth in claim 4 with the addition of a locking ring having a transverse slot to receive said pin and being rotatable by said pin to engage said transverse grooves of all said lead-carriers except the one occupied by said pin to lock all said lead-carriers except that engaged by said pin against movement in said guides.

10. The pencil set forth in claim 4 with the addition of means on each guide cooperating with said pin upon relative rotation of said casing sections in opposite directions when a lead-carrier is projected to lock said lead-carrier against retraction into the casing and release the lead-carrier respectively.

HALSEY MONROE LARTER.
